UNITED STATES PATENT OFFICE.

DAVID E. VANDERVEER, OF LOS ANGELES, CALIFORNIA.

AUTOMOBILE-CURTAIN WINDOW.

1,320,998.

Specification of Letters Patent. Patented Nov. 4, 1919.

Application filed November 19, 1918. Serial No. 202,854.

To all whom it may concern:

Be it known that I, DAVID E. VANDERVEER, a citizen of the United States, residing at Los Angeles, in the county of Los Angeles and State of California, have invented new and useful Improvements in Automobile-Curtain Windows, of which the following is a specification:

My invention has relation more specifically to a window frame construction, adapted to be secured in the curtains of vehicle tops.

A main object of my invention is to provide a combination metal and wood frame construction in which the attaching means mounted on the metal member to secure the parts of the frame together are adjustable.

Another object of my invention is the provision of a channeled form of the metallic member of the frame to insure lightness of construction, and thus prevent sagging of the flexible material to which the frame is secured.

A further and important object of my invention is to provide a frame in which the metallic member is formed of continuous channeled sheet metal, and which may be bent into a variety of shapes and forms.

I am aware that automobile curtain window frames have been used in a variety of constructions for automobile tops or curtains, but these frames have generally been formed of a wooden member and a cast metallic clamping member having lugs formed integrally therewith. While this construction has proven more or less efficient, yet on account of the weight of the cast metallic member it has caused the automobile curtain to unduly sag and wrinkle, thereby presenting an unsightly appearance after they are in place.

By forming the metallic clamping member of channeled sheet metal, I am enabled to overcome the above recited difficulties, preventing the wrinkling of the flexible material to which the frame is attached, and insuring a satisfactory adjustment of the members when secured together.

I accomplish the above objects by means of the construction herein described and illustrated in the accompanying drawing, in which:

Figure 1 is a face view of one form of my improved frame. 55

Fig. 2 is an enlarged cross sectional view taken on line 2-2 of Fig. 1.

Fig. 3 is a rear face view of the metallic attaching member, parts being in section to disclose the attaching means. 60

Fig. 4 is an enlarged view of the rear face of the metallic frame member.

Fig. 5 is a perspective view of an automobile top provided with my improved window frames. 65

I have illustrated my improved frame as consisting of substantially crescent form, but it will be understood that I may form the same into a variety of shapes, curved or rectangular, as desired. 70

Referring more particularly to the drawing, 6 designates a frame member preferably formed of wood or similar material and of the configuration desired for the window opening. Frame 6 on its outer face is depressed as at 7 for the reception of the metallic hollow clamping member 8 formed of sheet metal. Member 8 is preferably formed in strips of the required length, and these strips are then cut in pieces, the end 9 being brazed together or secured in any other suitable manner. The pieces may be of a curved configuration such as shown in the rear curtain 10 of Fig. 5, the channels being bent in by any suitable means. 85

Mounted in the hollow clamping member 8 are a plurality of frame attaching members 12 preferably consisting of a rectangular head 13 which is chambered and slides in the recess 11 of member 8, and each has lugs 14 which project through the channel 15 formed by the edges of the clamping member 8, as clearly shown in Fig. 2 of the drawing, the width of the channel 15 being slightly greater than the diameter of the lugs 14. Lugs 14 are apertured and internally threaded for the reception of screws 16 which pass through a plurality of countersunk bores 17 formed in frame 6 to securely hold members 6 and 8 in rigid engagement with each other when mounted in the automobile curtain. 95

When the frame attaching members 12 are inserted in the channel member they are placed in the position so that they will register 105 with the bores 17 in member 6, and they are

fixed in such position by bending the edges of the channel member 8 adjacent the edges 18 of the heads 12 slightly inwardly as clearly shown in Figs. 2 and 4 of the drawing by means of any suitable tool.

It will be further noted that the hollow recessed clamping member forms an exceedingly light construction which, when attached to the wooden frame, will not sag the 10 curtains or flexible material to which the same is attached in the slightest degree. The frame when in place presents the same neat appearance as those frames in which the clamping member 8 is formed of solid 15 material.

In mounting my improved frame in an automobile curtain, an opening of the desired configuration is first formed in the outer curtain 19 and inner lining 20. The 20 edge of the opening of curtain 19 passes between the underface of clamping member 8 and the depressed face 7 of frame member 6. The lugs 14 of attaching members 12 passing therethrough obviates the necessity of tacking the flexible curtain 19 to the frame as 25 in other similar structures.

The inner peripheral edges of clamping member 8 protect beyond the inner peripheral edges of frame 6, thereby forming a 30 seat against which the glass plate rests. The screws 16 are screwed tightly into the threaded apertures of lugs, thus clamping curtain 19 securely to the frame. The inner lining 20 of the curtain is then drawn over 35 the exposed outer face of member 6 and secured to its inner peripheral edge in any suitable manner. The plate glass 21 is then put in place, as clearly shown in Fig. 2 of the drawing, and a comparatively thick taping or fabric bead 22 is then secured to the 40 inner peripheral wall of frame 6 by means of tacks 23 to hold the same in place, the flexible taping or bead taking up any excessive jar or vibration occasioned by the 45 movement of the vehicle.

By forming the clamping member 8 of sheet metal the necessity of employing a large number of patterns for forming castings required when cast clamping members 50 are used is obviated, thus materially reducing the cost of the frame. Also, by employing a hollow clamping member I am enabled to insert as many lugs 12 as desired

in the same, according to the thickness of the material of which the top is formed, 55 thus if the material of which a top is formed is exceedingly light, it will require a greater number of lugs to hold the frame in place therein.

It will be further noted that I have 60 formed an exceedingly light construction, and one that will subserve all the purposes of similar structures which are now generally employed.

What I claim is:

65

1. The combination with a vehicle curtain, consisting of a curtain formed of flexible material having a fabric lining, of a wooden frame having a central opening 70 therein, the curtain and lining therefore having openings to receive said frame, the edges of the lining around the opening being attached to the inner peripheral edge of the opening of said frame, a channeled retaining ring formed from sheet metal seated on said frame and overlapping the opening in said frame, a plurality of headed lugs 75 adjustably mounted in said channeled retaining ring, said lugs passing through said curtain, a glass mounted in said frame 80 and contacting with the overlapping edge of said retaining ring, a plurality of screws passing through said frame and engaging said headed lugs, and a flexible strip of fabric attached to the inner peripheral edge 85 of said frame, one edge of said strip bearing against said glass and serving to hold the same in place in said frame.

2. A vehicle curtain window frame, comprising a wooden base member recessed on 90 one face thereof, and provided with a plurality of countersunk bores extending therethrough, a channeled metallic member seated on said base member, a plurality of movable attaching lugs having threaded bores mounted in said channel member, said lugs adapted to enter the bores formed in said base member, and a plurality of screws adapted to engage 95 the threaded bores of the lugs mounted in said channel member to clamp both members in rigid engagement with each other.

In witness that I claim the foregoing I have hereunto subscribed my name this 8th day of November, 1917.

DAVID E. VANDERVEER.
